US0D1081193S

(12) United States Design Patent (10) Patent No.: US D1,081,193 S
(45) Date of Patent:  Jul. 1, 2025

(54) SHELF

(71) Applicant: Beauventures LLC, Raleigh, NC (US)

(72) Inventors: Hasem Basaran, Sheridan, WY (US);
Mücahit Kalkan, Sheridan, WY (US)

(73) Assignee: Beauventures LLC, Raleigh, NC (US)

() Term: 15 Years

(21) Appl. No.: 35/520,824

(22) Filed: Sep. 20, 2023

(80) Hague Agreement Data

Int. Filing Date: Sep. 20, 2023

Int. Reg. No.: DM/236711

Int. Reg. Date: Sep. 20, 2023

Int. Reg. Pub. Date: May 10, 2024

(51) LOC (15) Cl. 06-04

(52) U.S. Cl.

USPC D6/574
